TOOTHBRUSH

Donald W. Brooks, Oradell, N. J.

Application May 12, 1949, Serial No. 2,605

Term of patent 14 years

(Cl. D9—2)

To all whom it may concern:

Be it known that I, Donald W. Brooks, a citizen of the United States of America and a resident of Oradell, in the county of Bergen and State of New Jersey, have invented a new, original, and ornamental Design for a Toothbrush of which the following is a specification, reference being had to the accompanying drawing, forming a part thereof:

Figure 1 is a side elevational view of a toothbrush showing my new design.

Figure 2 is a top plan view of the toothbrush.

Figure 3 is a bottom plan view thereof.

Figure 4 is an elevational view of one end of the toothbrush.

Figure 5 is an end elevational view of the other end of the toothbrush, and

Figure 6 is an enlarged transverse sectional view on the plane of the line 6—6 of Figure 2.

I claim:

The ornamental design for a toothbrush, as shown.

DONALD W. BROOKS.
